UNITED STATES PATENT OFFICE.

CYRUS H. LOUTREL, OF SOUTH ORANGE, NEW JERSEY, ASSIGNOR TO THE NATIONAL LOCK WASHER COMPANY, OF NEWARK, NEW JERSEY, A CORPORATION OF NEW JERSEY.

NUT-LOCK.

1,135,597.

Specification of Letters Patent. Patented Apr. 13, 1915.

Application filed November 30, 1914. Serial No. 874,745.

To all whom it may concern:

Be it known that I, CYRUS H. LOUTREL, a citizen of the United States, residing at South Orange, Essex county, State of New

5 Jersey, have invented certain new and useful Improvements in Nut-Locks; and I do declare the following to be a full, clear, and exact description of the invention, such as will enable others skilled in the art to which

10 it appertains to make and use the same.

This invention relates to nut locks such as are formed from a helical segment, and has for its object to stiffen the nut lock so as to increase the resistance which it affords

15 against the clamping elements.

In the accompanying drawings Figure 1 is a plan view of the nut lock—Fig. 2 is an edge elevation of the nut lock looking toward the extremities of the segment—Fig. 3 an

20 edge elevation of the nut lock when viewed from a point at right angles to that in Fig. 2, and Fig. 4 is an edge elevation of the nut lock viewed from a point directly opposite to that of Fig. 3.

25 Similar numerals of reference denote like parts in the several figures of the drawing.

In carrying out this invention portions of the helical segment are bent or displaced transversely on lines that are substantially 30 tangential to the inner edge of the helical or to any imaginary line that is parallel to such edge.

Referring to the drawing, the numeral 1 is used to designate the nut lock generally 35 speaking, 2 designates the inner edge of the helical segment which forms the nut lock, 3 designates the outer edge of such segment, 4 designates the bent or displaced portions, and 5 designates the line from which 40 the bending or displacement is effected. The line 5 as it appears in the drawing is parallel to a tangent to the inner edge 2 of the segment, but, of course, this bending or displacement might be effected in any desired 45 form. Therefore, it is immaterial as to

where this line 5 is located so long as it is substantially parallel with the line that is tangential to the edge 2, or, in other words, such line must be substantially at right angles to a radius of the helical segment. 50 These bent or displaced portions 4 are preferably perfectly plain, but, of course, the bending may be effected in such manner that the portions 4 may have curved surfaces so long as the bending is effected on a line that 55 is substantially tangent to the inner edge of the helical segment or to any imaginary line/parallel to such edge.

What is claimed is:—

1. A nut-lock consisting in general form 60 of a segment of a helix, having intermediate its ends a portion or portions bent on lines substantially at right angles to a radius of the helix.

2. A nut-lock of helical form, with dia- 65 metrically opposed portions adjacent the outer edges of the nut-lock bodily thrown out of line with the helical surface of the body of the nut-lock.

3. A nut-lock of helical form, with dia- 70 metrically opposed segmental portions thrown out of line with the helical surface of the body of the nut-lock, one of said portions inclining upwardly and the other downwardly.

4. A nut-lock of helical form, with portions of the body intermediate its ends and at its outer edge bent out of line with the helical surface of the body of the nut-lock.

5. A nut-lock having the form of a helix, 75 the inner edge whereof is truly helical, while the outer portion presents surfaces generally helical but having a deflected portion, or portions, intermediate the ends of the body.

In testimony whereof I affix my signature 80 in presence of two witnesses.

CYRUS H. LOUTREL.
